FIG. 4.

UNITED STATES PATENT OFFICE

2,198,666

SYRINGE

Benjamin Gruskin, Philadelphia, Pa., assignor,
by mesne assignments, to Lakeland Foundation,
Chicago, Ill., a corporation of Illinois

Application September 30, 1936, Serial No. 103,339

4 Claims. (Cl. 128—215)

This invention relates to a device commonly known in the medical arts by the term "hypodermic" syringe.

It is an object of this invention to provide a syringe for medical use which may be accurately adjustable with respect to the body surface and which is so constructed and arranged that the distance of the insertion of the needle may be carefully controlled.

10 Another object of this invention is to provide a syringe having a resilient body contacting portion providing a pressure against which the needle must be inserted, thereby permitting a tension against which the needle must be projected.

15 A further object of this invention is to provide a syringe which is particularly adapted for medical use in intradermal injection.

An additional object of this invention is to 20 provide a syringe which will accurately and expeditiously permit the injection of extremely small doses, at the same time effectively preventing the absorption by the syringe of air or other foreign matter by so constructing the device as to prohibit any unauthorized movement of the plunger.

25 It is furthermore an object of this invention to provide a syringe, the plunger portion of which may be held in any adjusted position during loading or injection and which, moreover, will always be closed against a slight tension in order to permit uniform injection of a dose.

30 Numerous other objects and advantages will be apparent from a consideration of the following specification and drawing which disclose a few embodiments constructed in accordance with the principles of the present invention and in which,

35 Fig. 1 is a side elevation of a syringe made according to the present invention;

40 Fig. 2 is a top plan view of the syringe shown in Fig. 1;

45 Fig. 3 is a detailed fragmentary end elevation disclosing the method of inserting the needle in a portion of the body;

50 Fig. 4 is a fragmentary sectional elevation taken on the line 4—4 in Fig. 2;

Fig. 5 is a fragmentary sectional elevation showing an alternative type of structure;

55 Fig. 6 is a detailed perspective view showing the end of the syringe tube; and

Fig. 7 is a perspective view showing an alternative type of structure to that shown in Fig. 6.

The syringe, which comprises an embodiment disclosed for illustrative purposes, is of a conventional type comprising a tubular glass body

10 having conventional numerals indicating the calibration of the volume thereof, and a solid glass plunger 12 which is ground carefully to fit the bore of the tube. A conventional metallic head 14 is secured to one end of the glass tube and carries an injecting needle 16 having a pointed end and a minute opening extending longitudinally thereof and communicating with the bore in the glass plunger 12.

15 There is provided a thin, metallic, yoke-shaped piece 18 having opposed parallel fingers 20 extending forwardly and parallel to the needle 16 to approximately the same distance. The yoke member 18 at its opposite end is narrowed to approximately the width of the glass tube and is provided with opposed up-turned flanges 22, the central portion of which may be slightly rounded to securely grasp the body of the tube and having slightly out-turned upper portions 24 to permit placing over the body of the tube.

20 The sheet metal structure is preferably of a resilient or springy, thin sheet of metallic material and it will be seen that the flanges 22 may be forced over the glass body of the syringe near the end thereof, as shown in Figs. 1 and 2, and 25 will grasp the surfaces thereof to hold it in the position shown.

25 The needle, it will be noted, is positioned over the opening formed between the two fingers 20 of the yoke so that, when the lower side of the 30 fingers is placed against an area to be injected, force may be applied to tilt the needle into contact with the body whereupon the yoke and the fingers 20 will flex to permit the needle to be resiliently forced to an intermediate area, as shown 35 in Fig. 3.

35 The glass plunger at the righthand end, as shown in the figures, is upset to form a radially extending flange 26 over which is fitted a cup-shaped head 28 having a depressed thumb portion 30. The longitudinally extending walls 32 of the cup-shaped member are threaded at their lower ends to accommodate a corresponding threaded collar 34 having a central bore sufficient to be slipped over the plunger. The collar 34 is 40 provided with a slot and apertures 36 in which a special tool may be inserted in order to tighten or release the collar 34 in the cup member 28 and thus positively and rigidly engage the end of the plunger, as shown in Fig. 4.

45 An outwardly extending member 38 is secured to the collar 34 by soldering or may be made integrally therewith if desired and has therein a rectangular aperture 40 extending parallel to the axis of the plunger in which is secured, by means 50

55 of a screw 42, a retaining ring 44 and a lock washer 46.

of a set screw 42, a rectangular projecting bayonet finger 44.

The end of the glass tube away from the needle is provided with a conventional flange portion 46 which is engaged by an annular cup-shaped member 48 having an axially and a radially extending wall. The free end of the axially extending wall is provided with threads 49 which engage corresponding threaded portions on an annular collar 50, the inner bore of which fits freely over the body of the tube 10.

The collar is provided with oppositely disposed apertures 52 to permit its rotation into threaded engagement with the member 48 by means of a special tool fitting therein.

Soldered, or otherwise secured, to the cup is a supporting block 54 having a vertical, relatively narrow slot 56 extending downwardly from the top edge to a line removed from the bottom thereof. Extending across this slot is a pivot pin 58 upon which is mounted for slight arcuate movement a brake member 60 having a downwardly extending braking edge 62 and a rearwardly extending portion 64 on which is mounted a control button 66. A spring 68, positioned in the slot 56, is secured at its lower end to a projection in the side walls of the slot (not shown) and presses upwardly against the lower portion of the control arm 64. A second pin 70, fixedly positioned in the slot, serves as a stop to limit the movement of the braking member in a clockwise direction around the pivot 58.

The bayonet member 44, secured to the head of the plunger, is so situated as to pass through the groove 56 in the brake supporting block and fits slidably therein beneath the brake member 60, as shown in Fig. 4. The normal pressure of the spring 68 will tend to cant the brake member upwardly from the position shown in Fig. 4, to that shown in Fig. 1, whereby the forward edge of the braking edge 62 will press downwardly against the bayonet member 44 and engage it clamping against the bottom of the groove 56.

Thus, it will be possible to push the bayonet member 44 to the left, as shown in Figs. 1, 2 and 4; but if effort is made to retract it in a reverse direction, the brake member will be canted against the upper surface thereof and engage it with increasing force so that such movement will be effectively resisted. If force is applied to the button 66, however, as shown in Fig. 4, the braking edge 62 will be lifted away from the upper surface of the bayonet member thereby to free it.

This type of braking member is hereinafter referred to in the specification and claims as a "strutting type" of interlocking device. As is well recognized by those skilled in the art, this type of interlocking means in general comprises an arm or other member pivoted or otherwise adapted to incline to bring a biting tooth or edge into engagement with a cooperable braking member. Thus attention is particularly directed to the fact that the forward extremity of the edge 52 provides a biting tooth which, when the arm 60 is inclined, is brought into biting engagement with the bar 44. The biting tooth edge engages the bar in such a manner that if it is attempted to move the bar outwardly the tooth engages with increased force effectively and positively preventing this movement. On the other hand, the bar is freely movable in an inward direction.

A spring 72 is situated between the flange of the tube and the inner surface of the collar 34 and encircles the plunger for the purpose of normally urging the plunger outwardly of the syringe and

in a direction opposite to that upon which the action of the braking member is exerted.

In operation, the syringe is first supplied with the required quantity of material to be injected in the conventional manner by inserting the plunger to its fullest extent and then causing the dose of injectable material to be taken up into the body of the glass tube 10.

In the instant device the plunger will be maintained in its adjusted position by the brake mechanism contacting the bayonet finger 44 which will prevent motion to the right as in Figs. 1 and 2. However, the compression spring 72 will naturally create a force urging the plunger in the said direction. Therefore, by merely pressing downwardly the control button 66, the brake will be released and the spring will move the plunger out of the body of the syringe.

The brake may be released entirely or for as long or short a period as desired in order to permit retraction of the plunger to the desired degree and, after this condition has been reached, there will be assured that the combined compression of the spring 72 and the action of the brake will maintain the syringe in such position and prevent inadvertent ingress of air bubbles or other undesired matter.

Then, by the action of thumb pressure upon the thumb portion 30 formed at the head of the plunger in the usual manner, the injection may be made. It will be noted that the spring 72 will provide a slight tension against the thumb pressure which is preferable in such work as it enables injection of a fluid uniformly and evenly, even though it is desired to carry out the operation slowly. Moreover, there will be no tendency to inject at too rapid a rate or with varying or jerky pressures.

In addition, it will be noted that the injection may be stopped at any desired point, either temporarily or finally and the spring and brake will always maintain the plunger in its final position against any inadvertent or unauthorized movement. After withdrawing, or at any other time, it is merely necessary to release the brake by pressing the button 66 to permit the plunger to be withdrawn to any desired degree.

Referring to Figs. 5 and 6 there is disclosed a modified construction comprising a member 78 which is secured to the head of the syringe tube 10 in the same manner as the cup-shaped member 48 in the previous embodiment. The end of the plunger member 12 is provided with an annular cup-shaped member 80 engaging the upset portion at the end of the plunger in exactly the reverse fashion as compared to the cup-shaped member 28 in the other embodiment. Herein a plug 82 is threaded into the end of the annular cup-shaped member 80 with the aid of a slot 84 for the insertion of a screw driver and thus serves to completely engage the end of the plunger.

Secured to the member 80 is an upstanding, radially disposed arm 86 which, at its upper left-hand end as viewed in Fig. 5, is provided with a forwardly extending finger 88 which terminates in a lug or downwardly projected portion 90 which is so situated as to project below the outer cylindrical surface of the collar 78. This collar is provided with a series of grooves designed to permit passage of the lug 90 therepast.

The groove 92 extends completely through the collar and it would be possible, by passing the lug 90 through this groove, to permit use of the syringe through the full movement of the plunger, since, when the latter is so turned as to be

directed through groove 92, there is no impediment to its passage. However, the groove 92 is widened at its righthand end, as shown in Fig. 5, and connects at its central portion with the 5 groove 94 which runs in an annular direction for a short distance and then terminates in the longitudinally extending groove 96 directed toward the needle end of the syringe.

Thus, if the grooves and the finger are properly 10 proportioned, the device might be employed for the injection of small quantities of liquid. For instance, in a syringe, which it may be said holds 1 cc. for purposes of illustration, and it is desired to inject .1 cc., to do this the plunger would be 15 relatively in the position shown in Fig. 5. Thus, by accurate proportioning of the groove and finger and by positioning the lug 90 in the groove 94, the plunger will be retracted to accommodate the exact volume desired and it is merely necessary to press the plunger in the conventional 20 manner so that the lug 90 will pass longitudinally out of groove 96 and take the dotted-line position shown in Fig. 5.

Initially the plunger may be placed in this 25 dotted-line position and may be filled with the desired quantity of fluid by retracting through the groove 96 to the position shown in Fig. 6. It is preferred to employ the spring 72 in order to provide some tension against the application of 30 pressure for the purpose of improving and facilitating the actual injection of the fluid in the manner described above.

A still further modified form of collar 78 is 35 shown in Fig. 7 wherein additional grooves 98 and 100 are provided in stepwise formation. In using this form of construction, the operator is permitted to choose either of two injections, that is, by loading the syringe in the amount indicated by the position of the lug 90 in Fig. 7, a relatively 40 small injection may be made, whereas by loading the syringe so that the lug is retracted through the groove 96 and against the shoulder formed by the groove 94, an increased quantity of fluid may be taken up by the syringe and thus an injection 45 of increased size may be made.

It will be obvious that any number of such 50 steps may be provided for or that various other structures may be provided in order to control accurately the positioning of the plunger or the volume of fluid which it is desired to take up and eject.

It is thought that the invention and numerous 55 of its attendant advantages will be understood from the foregoing description and it is obvious that numerous changes may be made in the form, construction and arrangement of the several parts without departing from the spirit or scope of the invention, or sacrificing any of its at-

tendant advantages, the form herein described being a preferred embodiment for the purpose of illustrating the invention.

Having thus described the invention, what is claimed as new and desired to be secured by Letters Patent is as follows:

1. In a syringe having an injection needle or the like, resilient fingers adjacent said needle and generally parallel thereto, and adapted first to contact the surface to be injected and resiliently 10 resist approach of the needle whereby said needle may be moved toward a position where it is interposed between said spring fingers by flexing said fingers during use.

2. An injection needle having means thereon 15 resiliently to resist approach of the needle to injecting position, said means comprising resilient spring fingers arranged in a plane at one side of the needle and extending generally parallel therewith to a point adjacent the end of the needle 20 whereby said needle may be moved toward a position where it is interposed between said spring fingers by flexing said fingers during use.

3. In an injecting device having an injection needle or the like, a resilient member associated 25 with said needle, said resilient means comprising a pair of spring fingers mounted on the syringe, said fingers being generally parallel and generally co-extensive with the needle, means to cause said resilient member to contact a surface before 30 application of a needle thereto, and means to insert a needle against the resilient flexing of said resilient member whereby said needle may be moved toward a position where it is interposed between said spring fingers by flexing said fingers 35 during use.

4. A syringe having a body and plunger operative in the body to take up and expel fluid, resilient spring means operatively associated with the plunger for urging said plunger outwardly 40 of the body, and interlocking means operatively connected to the plunger and the body, said interlocking means being operative to position the plunger with respect to the body in at least one intermediate position, said interlocking means 45 comprising an engageable finger and recess means adapted to selectively accommodate said finger, said recess means having a shoulder positively preventing outward movement of the plunger by said spring means and providing a 50 free passage in the opposite direction whereby the plunger may be freely actuated to expel the contents of the syringe against the spring tension only, and a second passage disposed axially of the syringe and being open ended in both axial 55 directions for permitting movement of said plunger completely out of said body.

BENJAMIN GRUSKIN.
